UNITED STATES PATENT OFFICE.

ROBERT S. WOODWARD, JR., OF PHILADELPHIA, PENNSYLVANIA.

POWER-TRANSMITTING APPARATUS.

1,346,625.

Specification of Letters Patent. Patented July 13, 1920.

Application filed September 4, 1919. Serial No. 321,524.

To all whom it may concern:

Be it known that I, ROBERT S. WOODWARD, Jr., a citizen of the United States, residing in Philadelphia, Pennsylvania, have invented the Power-Transmitting Apparatus, of which the following is a specification.

One object of my invention is to provide a relatively simple, substantial and positive system of apparatus for transmitting power from a source thereof to a member to be actuated; the invention more particularly contemplating a novel arrangement of parts for utilizing steel or other hard balls as a power-transmitting medium.

It is further desired to provide a novel form of jack or equivalent mechanical elevating apparatus with means whereby hard balls may be taken or received from a reservoir and so operated on by a suitable source of power acting as a pump as to raise or otherwise impart movement to the movable element of the jack; the arrangement being such that if desired a reverse operation of the motor or pump will cause a return of the balls to their reservoir and a lowering or reverse movement of the jack plunger or other movable element of the system.

These objects and other advantageous ends I attain as hereinafter set forth, reference being had to the accompanying drawings, in which,

Figure 1 is a longitudinal vertical section, to some extent diagrammatic, illustrating my invention as applied to a dentist's or similar chair;

Fig. 2 is a vertical section on the line 2—2, Fig. 1;

Fig. 3 is a section on the line 3—3, Fig. 2; and

Fig. 4 is a horizontal section also diagrammatic and illustrating a modification of the invention.

In the above drawings 1 represents the hollow base or foot of the chair or other structure to which my invention is applied and this is illustrated as consisting of a vertically mounted cylinder 3 having in the present case a telescopic plunger formed with an outwardly flanged tubular portion 8 closely and slidably fitting within said cylinder. The upper end of said portion is inwardly flanged for the reception of the outwardly flanged lower end of the second part 2 of the plunger. A reversible pump 5 suitable for forcibly moving steel or other hard

balls in either of two directions is connected to the lower part of said cylinder.

In a typical construction such a pump would consist of a cylindrical barrel having mounted within it a helical propelling member or rotor designed to be driven in either direction by a suitable source of power such as an electric motor 6. This latter is shown as electrically connected to a controller 9 governed by a foot actuated member 7 so that current may be supplied to it to drive the rotor either in a direction to force the balls into the cylinder 3 or to draw them out of the same as when they are supplied to its barrel by reason of the pressure exerted by the plunger 2.

At any suitable point within the base or casing 1 is mounted a reservoir 4 communicating with the ball pump 5 in such manner as to permit flow of balls 10 thereto under the action of gravity when the rotor in said pump is driven in one direction and to receive balls from the pump when the latter is driven in the opposite direction.

In the drawing the plunger 2—8 is shown as raised to its maximum extent and if it is desired to lower it, the foot-actuated member 7 of the controller 9 is so moved as to cause the electric motor to turn the rotor of the pump in a direction causing it to take balls from the cylinder 3 and forcibly deliver them into the reservoir 4. As a result the plunger with whatever structure is carried thereby, falls under the action of gravity.

When on the other hand it is desired to force the plunger 2 out of the cylinder 3, the member 7 of the controller 9 is so operated as to cause the rotor of the pump 5 to take the balls from the reservoir 4 under the action of gravity and forcibly deliver them into the cylinder 3 so that they act on the plunger 2 and forcibly raise it, moving it out of said cylinder to any desired extent.

Thereafter current may be cut off from the motor 6 by causing or permitting the arm 7 to move to its neutral or off position, and said plunger will remain in its given position until the pump is again put in operation to further raise it or to remove the balls from the cylinder 3 and permit it to lower.

If desired the motor and pump may be designed for operation in but one direction and a valved by-pass 11 be provided between the cylinder and the reservoir. In such case after the plunger had been raised the open-

ing of the valve 12 in said by-pass would permit flow of balls from the cylinder to the reservoir and allow the plunger to lower.

I claim:

5. 1. The combination of a cylinder; a plunger operative therein; a reservoir; a pump connecting the reservoir and the cylinder; a motor for driving the pump, means for controlling the motor; and a series of 10 relatively hard balls movable by the pump from the reservoir to the cylinder to actuate the plunger.
2. The combination of a cylinder; a plunger operative therein; a reservoir; a 15 body of relatively hard balls; and a reversible pump connected to force the balls from the reservoir to the cylinder or vice versa.
3. The combination of a cylinder; a 20 plunger operative therein; a reservoir; a pump connected between the reservoir and the cylinder and including a helically formed rotor; a motor for driving said rotor; and a

body of relatively hard balls in the reservoir, cylinder and pump.

25

4. The combination of a cylinder; a plunger operative therein; a pump connected to the cylinder; a reservoir connected to the pump; and balls movable by the pump from the reservoir into the cylinder.

30

5. The combination of a cylinder; a plunger operative therein; a pump connected to the cylinder; a reservoir connected to the pump; and balls movable by the pump from the reservoir into the cylinder, said 35 reservoir being mounted to deliver balls to the pump under the action of gravity.

35

6. The combination of a cylinder; a plunger operative therein; a reservoir; a pump connected to the reservoir and cylinder; balls in the reservoir movable by the 40 pump into the cylinder; a reversible motor for actuating the pump; and a controller for causing reversal of the motor at will.

40

In witness whereof I affix my signature. 45

ROBERT S. WOODWARD, JR.
